DESIGN FOR A KNITTED REUPHOLSTERING ENVELOPE

Walter L. Fry, Bloomfield Hills, Mich.

Application January 9, 1937, Serial No. 66,969

Term of patent 14 years

To all whom it may concern:

Be it known that I, Walter L. Fry, a citizen of the United States, residing at Bloomfield Hills, county of Oakland, in the State of Michigan, have invented a new, original, and ornamental Design for a Knitted Reupholstering Envelope of which the following is a specification, reference being made to the accompanying drawing, forming part thereof.

Fig. 1 is a front view, in perspective, of a knitted reupholstering envelope, showing my new design.

Fig. 2 is a rear view thereof.

I claim:

The ornamental design for a knitted reupholstering envelope as shown.

WALTER L. FRY.
